US0D1023121S

(12) **United States Design Patent** (10) **Patent No.:** **US D1,023,121 S**
(45) **Date of Patent:** **** Apr. 16, 2024**

(54) **GLASSES FRAMES**

- (71) Applicant: **PAIR Eyewear, Inc.**, New York, NY (US)
- (72) Inventors: **Nathan Kondamuri**, Brooklyn, NY (US); **Sophia Edelstein**, Brooklyn, NY (US); **Lee Zaro**, Rancho Palos Verdes, CA (US)
- (73) Assignee: **PAIR EYEWEAR, INC.**, New York, NY (US)
- (**) Term: **15 Years**

(21) Appl. No.: **29/914,182**

(22) Filed: **Oct. 13, 2023**

Related U.S. Application Data

- (62) Division of application No. 29/775,184, filed on Mar. 22, 2021.
- (51) **LOC (14) Cl.** **16-06**
- (52) **U.S. Cl.** **USPC .....** **D16/328**
- (58) **Field of Classification Search**

(57) **CLAIM**

The ornamental design for glasses frames, as shown and described.

DESCRIPTION

FIG. 1 is a front perspective view of glasses frames; FIG. 2 is a front view of the glasses frames;

FIG. 3 is a rear view of the glasses frames;

FIG. 4 is a right side view of the glasses frames;

FIG. 5 is a left side view of the glasses frames;

FIG. 6 is a top view of the glasses frames; and,

FIG. 7 is a bottom view of the glasses frames.

1 Claim, 4 Drawing Sheets
